UNITED STATES PATENT OFFICE.

JOHN H. SMITH, OF PHILADELPHIA, PENNSYLVANIA, ASSIGNOR TO WESTINGHOUSE ELECTRIC & MANUFACTURING COMPANY, A CORPORATION OF PENNSYLVANIA.

CONDENSER.

Application filed October 30, 1926. Serial No. 145,198.

My invention relates to condensers of the surface type and has for its object to provide apparatus of the character designated, equipped for cutting out of operation a portion of its tube nest while another part is in operation, and wherein more efficient operation of the condenser is secured when a section is cut out of operation.

More specifically the object of my invention is to provide apparatus of the character designated wherein all of the condensable vapors passing into the condenser are forced to go through a cooled portion of the tube nest when another portion is cut out of operation.

These and other objects are secured by apparatus made in accordance with my invention and illustrated in the accompanying drawings wherein:

20 Fig. 1 is a side elevation partly in section and with parts removed, of a condenser made in accordance with my invention;

25 Fig. 2 is an end view of the condenser shown in Fig. 1 and partly in section to show the interior construction of the water box;

Fig. 3 is a transverse sectional view taken along the plane III—III of Fig. 1.

In the operation of surface condensers, it 30 has been found desirable to provide divided flow means for the cooling water passing through the tubes thereof in order that a portion of the tubes may be cleaned at a time without totally interfering with the operation of the condenser. Difficulties have been encountered, however, in operating a condenser of this character with a portion of the cooling tubes cut out of service due to condensable vapors passing directly to the 40 air offtake of the condenser without first coming in contact with sufficient cooling tubes. This action has greatly reduced the vacuum obtainable in the condenser and has, at times, seriously interfered with the operation of the power plant.

In accordance with my invention, the above enumerated difficulties have been overcome by providing, in a condenser of the character described, an improved air offtake 50 whereby, when cooling water is cut off from a section of the tube nest, the condensable vapors are directed through a cooled section of the tube nest. I furthermore so arrange the air removal means that air and non-condensable vapors are removed only from a 55 cooled section of the tube nest when a portion thereof is cut out of service. During such times the air removal apparatus normally operating to remove air and non-condensable vapors from all sections of the tube nest is all utilized in association with the active section.

60 Referring now to the drawings for a better understanding of my invention I show in Figs. 1 to 3, inclusive, a condenser comprising a shell 10 encompassing a tube nest 11 of the well-known radial flow type. The condensable vapors are admitted into the shell of the condenser through an inlet 12 and condensate is removed therefrom from a hot-well 13. At each end of the condenser shell are attached water boxes 14 and 16. The water boxes 14 and 16 are each divided by a partition as shown at 17 in Fig. 2. Cooling water passing through the tube nest is admitted into the water box 16 through inlets 21 and 22 and, after passing through the tubes is discharged from the opposite end through conduits 23 and 24. Whenever it is desired to cut out a section of the tube nest 70 for cleaning or other purposes, the conduits, such as 22 and 24 on one side of the condenser are closed off as by means of valves 26 and 27. Thereupon no cooling water passes through that side of the water box 75 and tube nest controlled by said conduits and the water box may be entered as by means of doors 28—28 provided on the head of the water box and the tubes cleaned.

80 Disposed centrally of the tube nest 11 is an air offtake 31. The air offtake 31 is a box-like structure extending longitudinally from end-to-end of the tube nest and provided along each of its sides with ports such as 32—32 for the admission of air and non-condensable vapors thereto. Disposed above the air offtake 31 is a pan 33 into which condensate from the tubes directly above the air offtake falls and which drains downwardly into the shell of the condenser through 90 notches provided in the pan as at 34—34 adjacent a tube support 36.

95 In accordance with my invention I provide the air offtake 31 with solid partition means 37 extending from end-to-end thereof. The partition means 37 divides the air offtake 31 into two noncommunicating compartments 100 38 and 39. The compartment 38 communi-

cates, through its ports 32 with the left hand side of the tube nest 11 as shown in Fig. 3, while the compartment 39 communicates through its ports 32 with the right hand side of the tube nest 11, so that each of said compartments communicates with a portion of the tube nest corresponding to the division of water flow through said tube nest.

The air and non-condensable gases from 10 the compartment 38 are removed through a conduit 41 and the air and non-condensable gases from the compartment 39 are removed through a conduit 42. The conduits 41 and 42 are each provided, exteriorly of the condenser shell, with valves, as 43 and 44, whereby the flow of air and non-condensable gases from either of the compartments may be shut off.

After passing through the valves 43 and 20 44 the air and non-condensable gases from both compartments 38 and 39 passes into a common conduit 46. The conduit 46 has connected thereto suitable air removal means, such as ejectors 47 and 48. Either of the 25 ejectors 47 or 48 may be taken out of service by closing a valve 49 or 51 provided in a branch conduit leading thereto from the conduit 46. By the arrangement of air offtake and air removal means just described, the 30 ejectors 47 and 48 may operate to remove air and non-condensable gases from both of the compartments 38 and 39 or, with either the valve 43 or 44 closed, both ejectors may operate to remove both air and non-condensable 35 gases from one of the compartments 38 or 39. Preferably, when cooling water is passing through a portion only of the tube nest 11, both of the ejectors 47 and 48 are utilized to remove air and non-condensable vapors 40 from one of the compartments 38 or 39.

From the above description it will be apparent that the gases to be condensed entering the condenser through the inlet 12 when one side of the tube nest is cut out of operation and the conduit 41 or 42 leading from the air offtake communicating with said side is shut off, would tend to follow the path of least resistance direct to the active side of the air removal means. While, in normal operation, with cooling water flowing through all of the tubes and with both sides of the air removal means operating to remove air and non-condensable gases there is substantially an equal distribution 55 of the entering fluid throughout the nest, this condition does not prevail when cooling water is not circulating through a portion of the nest and the associated ports of the air removal means are rendered ineffective. Instead of the normal flow to substantially all portions of the nest, the entering fluid assumes a path, in general, toward the active ports of the air removal means and any tendency which the entering fluid may have to 60 permeate through the inactive portion of the

nest is partially offset by the active current set up by the air removal means on the active side. Furthermore, gases are drawn from the inactive side through the lower portion of the nest to the air removal means on 70 the active side.

In order to insure that air and non-condensable gases from any portion of the condenser, before entering the air offtake, will come in contact with a portion of the tube 75 nest through which cooling water is passing, when another portion is cut out of service, I provide baffle means extending substantially from tube sheet to tube sheet of the condenser within the tube nest. The baffle 80 means may be horizontally disposed and comprise a plate such as 51' arranged beneath the air offtake 31 as shown in Fig. 3. With this form of baffle, assuming the right hand side of the tube nest, as seen in Fig. 3, out of operation, and the valve 44 closed to prevent the removal of air and non-condensable vapors from the compartment 39, the gases in the upper region of the right hand side will pass to the left above the drain pan 33, 85 while such gases as may find their way further into the right hand portion of the nest will pass to the left below the baffle 51'; in either case, these gases must come in contact with a considerable number of tubes through 90 which cooling water is circulating before the air and non-condensable vapors are removed through the ports 32 of the offtake compartment 38. It will thus be seen that I have provided an efficient means for preventing 100 the by-passing of gases directly from the inactive side to the air offtake and that all gases which are removed by the air offtake must first come in contact with a considerable number of cooled tubes and that the 105 drain pan 33 is so arranged as to constitute a baffle: thus I am able to provide the baffling means by using only one additional element, namely, the baffle 51'.

While this baffling means is a valuable contributory means it is not essential to the operation of my improved condenser for it is obvious that vapors from the inactive portion of the nest will come into contact with some of the cooled tubes even with the plate 110 51 removed and the drain pan 33 spaced above the offtake so as to be ineffective as a baffle.

As a large volume of fluid entering the inactive side of the nest will pass above the air offtake to the active side, I may use only the drain pan 33 as my baffling means and rely upon cooled tubes between the ports 32 of the active side and that region of the inactive side, which extends from the air offtake 115 downwardly, to condense the condensable vapors which pass below the offtake from the inactive to the active side.

While, as the preferred form of my invention, I have shown a condenser in which 120

one-half of the tube nest may be cut out, it will be obvious to those skilled in the art that, should it be desired, the condenser may be so arranged that two or more equal or 5 unequal portions may be selectively cut out of service while the remaining portion or portions remain in service.

From the foregoing it will be apparent that I have devised an improved condenser 10 wherein a portion of the tube nest may be cut out of operation for cleaning and other purposes and wherein, under such conditions, the efficient operation of the condenser is not impaired.

15 While I have shown my invention in several forms, it will be obvious to those skilled in the art that it is not so limited, but is susceptible of various other changes and modifications, without departing from the 20 spirit thereof, and I desire, therefore, that only such limitations shall be placed thereupon as are imposed by the prior art or as are specifically set forth in the appended claims.

25 What I claim is:—

1. In a surface condenser, a tube nest, a water box having a partition therein dividing it into sections each controlling the flow of cooling water through a portion of the 30 tube nest, an air offtake having partition means therein forming compartments communicating with the portions of the tube nest, means for shutting off the flow of water through any one of the sections in the water 35 box, means for shutting off the flow of air and non-condensable vapors through any one of the compartments, and baffle means for directing condensable vapors through a cooled portion of the tube nest when the 40 flow of water and air through another portion is shut off.

2. In a surface condenser, a tube nest, a water box having a partition therein dividing it into sections each controlling the flow 45 of cooling water through a portion of the tube nest, an air offtake disposed within the tube nest and having a partition provided therein forming compartments communicating with the portions of the tube nest, means 50 for shutting off the flow of water through any one of the divisions of the water box, means for shutting off the flow of air and non-condensable vapors through any one of the compartments, and baffle means for conducting condensable vapors through a cooled 55 portion of the tube nest when the flow of water and air through another portion is shut off.

3. In a condenser of the surface type, a 60 shell, a tube nest disposed within the shell, an air offtake centrally disposed of the tube nest and extending longitudinally thereof from end-to-end of said tube nest, a water box divided into compartments each controlling 65 the flow of water through a portion of

the tube nest, means dividing the air offtake into compartments extending substantially from end-to-end of the tube nest, each of said compartments communicating with a portion of the tube nest, separate conduits for the removal of air and non-condensable gases from each of the compartments, means for shutting off the flow of water through a portion of the tube nest, means for shutting off the flow of air from the compartment of the 70 air offtake communicating with said portion of the tube nest, and baffle means extending substantially from end-to-end of the tube nest for directing vapors through a cooled portion of the tube nest when a portion is 80 cut out.

4. In a surface condenser of the radial flow type embodying separate means for effecting a flow of water through different portions of the tube nest and air removal 85 means communicating with said portions, means for shutting off the flow of water through a portion of the tube nest and for shutting off the removal of air and non-condensable gases from said portion, and a 90 baffle extending substantially from end-to-end of the tube nest effective when the flow of water and air through a section is shut off to direct vapors entering the condenser through a cooled section of tubes toward its 95 corresponding air removal means.

5. In a surface condenser of the radial flow type embodying a tube nest and a divided water box with means for at will directing the flow of cooling water through all 100 or a portion of said tubes, an air offtake comprising a divided box-like structure extending substantially from end-to-end of the tube nest and having compartments with ports communicating with the portions 105 of said tube nest corresponding to the division of water flow through said tube nest, separate conduits for the removal of air from each of the compartments, means for shutting off the flow of air and non-condensable gases from any one of the compartments, and a baffle member associated with the air offtake for directing the flow of vapors through a section of the tube nest associated with an active compartment of the air 110 offtake when the conduit leading from one of the compartments is closed.

6. In a surface condenser of the radial flow type, a tube nest, a centrally disposed air offtake, means dividing the air offtake 115 into compartments communicating with different portions of the tube nest, separate air removal means communicating with the compartments, and a centrally disposed baffle member extending substantially from end-to-end of the tube nest for directing the flow of vapors toward the tubes associated with an active compartment of the air offtake when the air removal from one of the compartments is shut off.

7. In a surface condenser, a tube nest, a water box divided into a plurality of sections for selectively controlling the flow of water through corresponding portions of the tube nest, means providing an air offtake passage for each controllable portion of the tube nest, said air offtake passages extending between the tubes of their respective portions of the nest, and means for selectively controlling the removal of air and non-condensable gases through each offtake passage.

8. In a surface condenser, a tube nest, a water box divided into a plurality of sections for selectively controlling the flow of water through corresponding portions of the tube nest, means providing an air offtake passage for each controllable portion of the tube nest in juxtaposed relation with respect to the tubes of its respective portion of the nest, and means for selectively controlling the removal of air and non-condensable gases through each offtake passage.

9. In a surface condenser, a tube nest, a water box divided into a plurality of sections for selectively controlling the flow of water through corresponding portions of the tube nest, means providing an air offtake passage for each controllable portion of the tube nest, and means for selectively controlling the removal of air and non-condensable gases through each offtake passage.

10. In a surface condenser, a tube nest, a water box divided into a plurality of sections for selectively controlling the flow of water through corresponding portions of the tube nest, means providing an air offtake passage for each controllable portion of the tube nest, and a drain pan associated with the offtake passages for receiving condensate and directing condensable vapors through a cooled portion of the tube nest

when another portion of the tube nest is cut out of service.

11. In a surface condenser, a tube nest, a water box divided into a plurality of sections for selectively controlling the flow of water through corresponding portions of the tube nest, means providing an air offtake passage for each controllable portion of the tube nest, baffle means at the upper extremity of the offtake passages and baffle means at the lower extremity of the offtake passages for directing condensable vapors through a cooled portion of the tube nest when another portion of the tube nest is cut out of service.

12. In a surface condenser, a tube nest, a water box divided into a plurality of sections for selectively controlling the flow of water through corresponding portions of the tube nest, means providing an air offtake passage for each controllable portion of the tube nest and a transversely extending baffle member below the offtake passages for directing condensable vapors through a cooled portion of the tube nest when another portion of the tube nest is cut out of service.

13. In a surface condenser, a tube nest, a water box divided into a plurality of sections for selectively controlling the flow of water through corresponding portions of the tube nest, means providing an air offtake passage for each controllable portion of the tube nest, and baffle means arranged above and below the offtake passages for directing condensable vapors through a cooled portion of the tube nest when another portion of the tube nest is cut out of service.

In testimony whereof, I have hereunto subscribed my name this 30th day of September, 1926.

JOHN H. SMITH.
